UNITED STATES PATENT OFFICE.

JOHN W. FAIRBANKS, OF MARION, OHIO.

EXCAVATING-MACHINE.

1,143,619.

Specification of Letters Patent. Patented June 22, 1915.

Application filed April 4, 1914. Serial No. 829,579.

To all whom it may concern:

Be it known that I, JOHN W. FAIRBANKS, a citizen of the United States, residing at Marion, in the county of Marion and State 5 of Ohio, have invented a new and useful Excavating-Machine, of which the following is a specification.

This invention relates to excavating machines of that type utilizing a scoop or dipper designed to be thrust into the material being excavated, one of the objects of the invention being to provide a boom made up of telescoping members, one of which supports a thrusting mechanism whereby the 10 front member of the boom is projected forwardly, thus to exert a thrusting action against the material being excavated by the scoop or dipper carried by the boom.

A further object is to provide means 20 whereby the scoop or dipper will be secured against swinging movement relative to the boom until a predetermined position has been reached by the boom whereupon the said scoop or dipper can be unlatched and 25 its contents caused to be discharged.

A further object is to provide a machine of this character in which the boom is so mounted as to enable the scoop to be thrust into the dirt, slate, shale, coal and the like 30 to be removed, with much less power than heretofore necessary where the booms have been so mounted as to necessitate cutting downward by the buckets through the grain of the material to be excavated.

35 A further object is to provide a machine which will so operate, especially in digging coal, as to reduce the amount of waste, commonly called slack.

As is well known, the usual method of 40 excavating material is to utilize a dipper or scoop upon the end of a boom extending along a radius intersecting the grain of the material to be excavated. Thus as the scoop or dipper is brought into action it is necessary for it to cut downwardly through the 45 grain of the said material, thus not only requiring greater power but tending to break up the material into fine particles of little value.

50 As hereinbefore pointed out, one of the objects of the present invention is to provide a machine the scoop or dipper of which is capable of being thrust longitudinally of the grain of the material to be excavated so 55 that the tendency of breaking up the ma-

terial is greatly reduced and less power is required.

Another object of the present invention is to provide a boom which is so constructed as to enable the excavated material to be discharged at a distance from the machine substantially equal to the length of the boom. 60

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the 70 scope of what is claimed, without departing from the spirit of the invention.

In the accompanying drawings the preferred form of the invention has been shown.

In said drawings:—Figure 1 is a side elevation of the machine, one of the positions of the boom and scoop being indicated by dotted lines. Fig. 2 is an enlarged vertical longitudinal section through the scoop and the adjacent parts. Fig. 3 is an end elevation of the scoop. 75 80

Referring to the figures by characters of reference, 1 designates a truck the wheels 2 of which may be designed to run either upon the ground or upon a track, this truck being propelled by any suitable mechanism, indicated generally at 3. A turntable 4 is mounted on the truck and supports a platform 5 on which a motor 6, a boiler 7, and certain controlling mechanism indicated at 8' may be mounted. 85 90

Hingedly connected to one end portion of the platform 5 is a telescopic boom 8 made up of an inner tubular member 9 and an outer slidable member 10, the said member 9 being provided, at its outer end, with a sheave 11 to the block 12 of which is connected one end of a cable 13 which cable is extended into engagement with a sheave 14, thence back into engagement with sheave 100 11, and thence again in engagement with sheave 14, and finally downwardly to the controlling mechanism 8'. The sheave 14 is supported by an upstanding frame 15 suitably braced, as at 16. By means of the cable 105 13 and its operating mechanism, the boom can be swung upwardly and downwardly.

The member 9 of the boom carries a motor 17 designed to drive gearing 18, there being a gear 19 meshing with a rack 20 110

formed longitudinally upon the boom member 10 so that, when the motor 17 is actuated, said boom member 10 can be shifted longitudinally either outwardly or inwardly relative to the member 9.

Secured to the outer end of the boom member 10 is a hinged scoop or dipper 21 at the back of which is arranged an upstanding arm 22 preferably in the form of a loop 10 having a cross pin 23. A frame 24 is fixedly secured to the member 10 and extends upwardly therefrom and pivotally mounted in this frame is a locking dog 25 having an arm 26 to which is secured the tripping cord 15 27 extending along the boom 8 and over suitably arranged guide sheaves 28. A spring 29 may be employed for holding the dog 25 normally in locking position where it will engage the pin 23 when the scoop or 20 dipper 21 is moved to active position. A controlling line 29 is secured to the upper end of arm 22 and passes over a guide sheave 30 carried by frame 24 and also over any other suitable arrangement of guide sheaves 25 and thence downwardly to the controlling mechanism 8'.

It is to be understood that the controlling mechanism 8' does not, specifically, constitute any part of the present invention. 30 Various means may be provided for taking up and paying out the cable 13 and the line 29. It is merely essential that the mechanism be such as to enable the line 29 to be overhauled during the hoisting of the boom. 35 It is also desirable to use some form of brake mechanism whereby the paying out of the line 29 can be retarded during the dumping operation so that the dumping can be effected without shock. Obviously various means can be provided for these purposes and consequently it has not been deemed necessary to go into a detailed description and illustration thereof, particularly in view of the fact that they do not in 40 themselves constitute any part of the present invention.

In using the machine herein described, the motor 17 is put in operation so as to retract the boom section 10 and the arm 22 is 50 shifted so as to cause dog 25 to engage pin 23 and thus lock the scoop or dipper in

active position. The boom is then lowered by means of the cable 13 and to the position indicated by dotted lines in Fig. 1. The motor 17 is then operated to thrust the section 10 outwardly from the section 9 so that the scoop or dipper will thus plow into the material to be excavated, the said scoop or dipper working into the material along the line of the grain thereof and as soon as it 60 has been filled, the scoop or dipper is raised by hoisting the boom 8 by means of cable 13. As before pointed out, during this hoisting of the boom, slack in the line 29 will be taken up. After the boom has been 65 elevated the desired distance, the same can be slued to one side and the tripping line 27 pulled so as to disengage dog 25 from pin 23. The line 29 can then be paid out gradually 70 so that the contents of the scoop or dipper 70 will be discharged without jar to the machine. The parts can then be retracted as before and the operation repeated.

It has been found that by utilizing a machine operating in the manner set forth, the 75 waste produced in excavating material such as coal, stone, etc., is reduced to the minimum and less power is required to thrust the scoop or dipper along lines parallel with the grain of the material than would be 80 necessary to thrust it downwardly across the grain, as is necessary where the boom is extended along a radial line intersecting the grain of the material.

What is claimed is:—

An excavating machine including a boom, a scoop hingedly connected to the boom, a looped handle upstanding from the scoop, a cross pin carried thereby, a dog for engaging the pin to lock the scoop against movement relative to the boom, and means connected to the arm for retarding the movement of the scoop to discharging position relative to the boom, and means for actuating the dog to release the arm.

In testimony that I claim the foregoing as my own, I have hereto affixed my signature in the presence of two witnesses.

JOHN W. FAIRBANKS.
